UNITED STATES PATENT OFFICE.

JOHN D. CONROY, OF CHOKIO, MINNESOTA.

WHEEL-SCRAPER.

1,253,155.

Specification of Letters Patent.

Patented Jan. 8, 1918.

Application filed May 15, 1917. Serial No. 163,753.

To all whom it may concern:

Be it known that I, JOHN D. CONROY, a citizen of the United States, residing at Chokio, in the county of Stevens and State 5 of Minnesota, have invented new and useful Improvements in Wheel-Scrapers, of which the following is a specification.

This invention relates to wheel scrapers, and more especially it is applicable to the 10 wheels of drills.

The purpose of the device is to scrape the mud from the periphery or tire of the wheel, so that the latter will not slip on the earth, and the object of the invention is to produce 15 a scraper of this character which is spring-pressed toward and preferably in contact with the rim of the wheel although it can be instantly thrown out of contact at any time, and also one in which the blade is reversible 20 when it becomes worn.

These objects are carried out by the construction hereinafter more fully described and claimed, and as shown in the drawings wherein:

25 Figure 1 is a perspective view in outline of the rear end of a Monitor drill or furrow opener with this attachment applied.

Fig. 2 is a side elevation of the attachment removed.

30 Fig. 3 is a similar elevation of the attachment as adapted for the Van Brunt drill or the Kentucky drill or others of like structure.

In Fig. 1 of the drawings I have used the 35 letter W to designate a wheel and B a box or hopper. The frame F of the Monitor machine is of tubing as shown, and the structure of my improved attachment is made accordingly when applied to this machine. The frame of other types of 40 machines is of angle-iron, and the structure of my attachment is slightly changed to adapt it thereto, although the general principle of either is the same.

45 Coming now to the details, the reference numeral 1 designates a shank which is tubular in Figs. 1 and 2 and flat in Fig. 3 as indicated at 1', the former being pierced with openings 2 and the latter with slots 2'. The

50 rear end of the shank is bent substantially at right-angles to a crank-arm 3 which would be a continuation of the tubular shank or a sleeve 3' attached to the rear end of the flat shank. The scraper itself is a blade or plate

55 4 substantially rectangular in contour and preferably flat, and to its rear side are at-

tached two loops 5 constituting bearings and which loosely embrace the crank arm at spaced points thereof. Coiled on the crank arm just inside the bearings are springs 6, 60 each having one end 7 attached to the arm and the other end 8 pressing the lower edge of the plate normally forward and into active contact with the periphery of the wheel W. Each corner, or two diagonally opposite corners, of the plate are pierced with openings 9 in which may be selectively inserted a screw-hook 10 held by nuts 11 set up tight against the opposite faces of the blade. Finally a chain 12 is provided, one 65 end being attached as at 13 to the box B at an appropriate point, and a proper link thereof is engaged with the hook when it is desired to tilt the blade so that its lower edge will not contact with the wheel. Obviously it is possible by disengaging this link and reengaging the hook with another link nearer the box, to throw the blade out of active position or in other words, to remove its lower edge so far from the wheel 70 that it no longer acts as a scraper. As seen in Fig. 1 the tubular shank 1 is slipped into a pipe of the frame F and held by screws or bolts passing through the frame and through the openings in the shank. Correspondingly the flat shank 1' shown in Fig. 3 is attached to the frame of other types of drills or similar machines, by laying the shank alongside the frame and passing bolts through the slots in the shank and through 75 openings in or formed in the frame at an appropriate point. When this scraper is not to be used at all, these fastening means may be removed and the entire attachment withdrawn. When the scraper is applied, 80 it may be thrown temporarily out of action as suggested and at times when it is desired that it shall not work. The use of a device of this class is too well known to need any amplification here. A particular feature of 85 the invention is the possibility of reversing the scraping blade or plate when its lower edge becomes worn. This is done by disconnecting the springs where they are attached to the crank arm, and slipping both 90 bearings and both springs off the extremity of the crank arm, then reversing the plate end for end, re-assembling the parts, and slipping them back into place again.

What is claimed as new is:—

1. In a wheel scraper, the combination with a support comprising a shank having

110

- means for attachment to the vehicle frame and carrying a right-angular crank-arm; of a scraping blade rectangular in contour and having openings at its obliquely opposite corners, bearings attached to the blade, and revolvably mounted on said crank-arm, a spring secured to the latter and pressing the lower end of the blade normally into contact with the wheel-rim, and a chain attached 5 at one end to the vehicle body and having a hook at its other end adapted to engage the opening in whichever end of the blade is uppermost, whereby said blade is rendered reversible.
- 15 2. In a wheel scraper, the combination with a support comprising a shank having means for attachment to the vehicle frame and carrying a right-angular crank-arm; of a scraping blade, bearings carried thereby 20 and revolvably mounted on said crank-arm, a spring secured to the latter and pressing the lower end of the blade normally into contact with the wheel-rim, the corners of said blade being pierced with openings, a 25 screw hook selectively mounted in one of

said openings at the upper end of the blade, and a chain attached at one end to the vehicle and having its links engageable with said hook, for the purpose set forth.

3. In a drill wheel scraper, the combination with a tubular shank bent at right angles into a crank-arm, both the shank and the arm being pierced with openings, fastening means through the openings in the shank whereby it may be attached to the frame of a drill, and a chain connected at one end with the box of the drill; of a rectangular scraping blade lying forward of said crank-arm, bearings on its rear face embracing the crank-arm, springs coiled on the latter between said bearings and each having one end engaging the arm and the other end pressing against the blade to throw its lower edge into active contact with the drill wheel, and means at the upper end of the blade selectively engaging the links of said chain, for the purpose set forth.

In testimony whereof I affix my signature.

JOHN D. CONROY.
